UNITED STATES PATENT OFFICE

CHARLES E. HOPPES, OF SPRINGFIELD, OHIO, ASSIGNOR TO THE EVERWEAR MANUFACTURING COMPANY, OF SPRINGFIELD, OHIO, A CORPORATION OF OHIO

PLAYGROUND APPARATUS

Application filed April 8, 1929. Serial No. 353,409.

This invention relates to merry-go-rounds of the type which are installed in playgrounds for the use of children.

One of the objects of the invention is to increase the ease with which the apparatus can be operated; a more specific object in this connection being to provide a simple and effective construction whereby anti-friction devices may be incorporated within the structure in connection with means for retaining lubricant therein.

A further object of the invention is to improve and simplify the frame structure which carries the running board or platform and controlling tongue.

Other objects will appear from the accompanying description and claim.

Referring to the drawings:

Fig. 1 is a top plan view of an apparatus embodying the improvement.

Fig. 2 is a vertical section of a portion of the same.

Fig. 3 is a vertical enlarged section of some of the parts shown in Fig. 2.

Fig. 4 is also an enlarged vertical section of some of the parts shown in Fig. 2.

Fig. 5 is a bottom plan view of the supporting base.

The supporting base of the structure consists of a metallic circular block 1 having a plurality of integrally formed bottom extensions 2, each strengthened by a web 3. To these extensions are secured channel members which form supporting feet. A pair of short channel members 4 are fastened to two opposite extensions 2, the inner ends of each of the channel members terminating at a point flush with the inner ends of the extensions to which they are fastened. Secured to the other two extensions 2 is a long channel member 5, the vertical webs 5' of which are received in recesses 6 which extends transversely across the under side of the block.

The block 1 has a central vertical bore in which is inserted with a tight fit the lower end of a standard 7, the standard being preferably secured in the block by a pin 8.

The upper end of the block 1 is recessed to form an annular pocket 9 and fitted to the standard 7 within this pocket is a ring 10

which forms one of the races for the rolls 11 of anti-friction bearings upon which are supported a revoluble head 12 within which is fitted the companion race ring 13; the ring 13 being secured in position in an annular recess in the head 12 by Babbitt material 14 or other suitable material.

The upper side of the head 12 has an annular socket 15 to receive the lower end of a tubular member 16. The upper end of this tubular member carries a second head 17, the lower side of which has a socket 18 which receives the upper end of the member 16. This second head 17 is formed on its upper side with an annular pocket 19, in the lower portion of which is one of the race rings 20 of another set of anti-friction rolls 21, this race ring being secured in position by Babbitt material 22 or other suitable material. The other race ring 23 of the bearing is fitted to the standard 7, a collar 24 being fastened by a set screw to hold the ring in position. The pocket 19 in the upper head is closed by a cap 25 fitted on the wall of the pocket.

Each of the heads 12-17 is provided with a plurality of integrally formed laterally extending sockets 26 which receive the ends of U-shaped tubular frame members 27 which extend radially and serve to support the wooden foot members 29, the wooden wall members 30 and the wooden ceiling deck or top members 31. The foot board members 29 and wall members 30 are carried directly by saddles 32 which in turn are secured to the lower portions of the frame members 27. A diagonal brace member 33 preferably extends from each saddle to the upper head 17 and a vertical brace member 34 is preferably interposed between each saddle and the upper portion of each frame member 27.

The ceiling members 31 are fastened at their outer ends to brackets 35 which in turn are secured to walls 30, while the inner ends of the ceiling members 31 are fastened between the flared portions of a pair of collars 36 which are fastened to the tubular member 16 by set screws.

To supply lubricant to the bearings the cap 25 has a removable plug 37 and the tubular member 16 a removable plug 38. Lubricant

inserted through the opening closed by the plug 38 finds its way between the standard 7 and the sleeve to the lower bearings while lubricant inserted through the opening closed by the plug 37 readily finds its way to the upper bearings. By reason of the fact that the bearings are located in pockets as described, the lubricant will be retained about the bearings.

10 Having thus described my invention, I claim:

15 An upright support, upper and lower revolvable heads mounted upon said support, a plurality of U-shaped members each having their free ends connected with said heads, said U-shaped members projecting radially, and foot boards supported by the outer ends of said U-shaped members.

20 In testimony whereof, I have hereunto set my hand this 19th day of February, 1929.

CHARLES E. HOPPES.
